(57) **CLAIM**

The ornamental design for a double bladed windshield wiper with a central sponge portion, as shown and described.

DESCRIPTION

FIG. 1 is a left side elevation view of a double bladed windshield wiper with a central sponge portion showing my new design, the opposite side being a mirror image.

FIG. 2 is bottom plan view thereof

FIG. 3 is top plan view thereof

FIG. 4 is an enlarged right end elevation view thereof, the opposite side being a mirror image; and,

FIG. 5 is a partial perspective view of the right end of the double bladed windshield wiper with a central sponge portion.
